10 Claims. (Cl. 66—168)

The present invention relates to a dust removing arrangement for circular knitting machines, and more particularly to apparatus for preventing dust developed by thread passing through thread guides at the top of the knitting machine to settle in the working area of the knitting machine.

Circular knitting machines have a plurality of knitting stations arranged around the circumference of the machine. At each knitting station, a thread package is mounted on a spindle, and the thread is guided upwards to a support on which a number of thread guides corresponding to the number of knitting stations are mounted. The thread passes through the thread guides and then downwardly again to thread transporting rollers, at least one of which is provided at each knitting station of the circular knitting machine.

The thread guides on top of the machine are part of electric thread breakage indicators which may indicate a thread breakage or stop the machine when one of the threads is broken, or when the thread supply on the respective spindle is exhausted.

It is known to mount a housing on top of a central post projecting upwards from the machine and to place thread breakage indicating devices within the housing, while the corresponding thread guides project outwardly from an annular wall of the housing. Due to the fact that the threads for the several knitting stations have to pass through the corresponding thread guides on top of the machine, substantial dust is developed which drops in the region of the center of the machine, and may settle on the working areas of the machine.

It is one object of the invention to prevent the settling of dust developed in this manner on the machine.

Another object of the invention is to blow air outwardly from the center of a circular row of thread guides on top of the machine so that dust produced by threads passing through the thread guides is blown in outward direction away from the machine and cannot settle on the same.

Another object of the invention is to place a blower which blows air in tangential directions along the entire periphery thereof at the center of the circle of thread guides on top of the circular knitting machine, so that the air stream produced by the blower reaches simultaneously all thread guides.

Another object of the invention is to mount the motor of the blower in a dust proof inner chamber located within the annular row of thread guides and thread breakage indicators.

With these objects in view one embodiment of the invention comprises a plurality of thread guides arranged in a circle, and means at the center of the circle for blowing air outwardly past all thread guides and beyond the same, so that dust produced by threads passing through the thread guides is blown away from the machine in outward directions and cannot settle at the working areas of the machine.

In accordance with a preferred embodiment of the invention, housing means are mounted on an upwardly projecting support on top of the machine, and include an inner annular wall forming an inner chamber for a

2

tangentially operating blower, and an outer wall forming an annular chamber surrounding the inner chamber and supporting a plurality of thread guides which outwardly project from the wall and are circumferentially spaced from each other. Both walls are formed with circumferentially spaced openings so that air passes from the inner chamber into the outer annular chamber and through the openings in the same. The air is guided by the openings, and preferably also by suitably shaped wall portion of the housing toward the outwardly projecting thread guides and beyond the same in outward directions so that dust blown off the thread guides is carried away from the center of the machine and cannot settle on the working areas of the same.

In the preferred embodiment of the invention, the inner chamber has a closed chamber portion in which the motor of the blower is located, and another chamber portion provided with an axial inlet, preferably covered by a filter, so that the rotor of the blower sucks the air in in axial direction and blows the air outwardly in tangential directions through the openings in the inner wall.

The outer wall preferably forms an annular gap with the inner wall, and part of the air blown into the annular chamber passes below a free annular edge of the outer wall where the thread guides are mounted so that also the inner portions of the thread guides are passed by air streams.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary elevation illustrating the top of a circular knitting machine; and

FIG. 2 is a fragmentary axial sectional view taken along line X—X in FIG. 1 and illustrating an embodiment of the invention with which the knitting machine of FIG. 1 is provided.

Referring now to the drawing, and more particularly to FIG. 1, a housing 16 is located at the top of a circular knitting machine, and carries a plurality of thread transporting rollers 17 spaced about the circumference thereof. The spacing between the transporting rollers 17 corresponds to the circumferential spacing of the knitting stations of the machine and a thread 67 is transported by each transporting roller 17 toward the needles which are located at the respective knitting stations. A thread guide 17a is mounted adjacent each thread transporting roller 17.

Housing 16 carries a corresponding number of outwardly projecting supporting rods 18 on which spindles 55 carrying thread packages 61 are mounted. Each thread package 61 supplies the thread required at the respective knitting station.

At the center of the housing 16, a central post 21 upwardly projecting along the main axis X—X of the machine, is provided. A ring 63 has a hub portion secured to post 21, and a plurality of radially projecting circumferentially spaced supporting rods 64 at whose outer ends thread guides 65 are mounted. A housing 62 is mounted on the top of post 21 and has circumferentially spaced openings 71. A plurality of thread guides 66 are mounted circumferentially spaced from each other and outwardly projecting from an annular outer wall of housing 62, one thread guide 66 being associated with each knitting station, and correspondingly with each thread package 61 and transporting roller 17. At each knitting station, a thread supplied by package 61 passes

through a thread guide 65, upwardly toward a thread guide 66 and then down again to a thread guide 17a and to a transporting roller 17.

Supporting post 21 is shown broken off in FIG. 1 and actually the post is much longer in vertical direction so that the slant of the thread portion between each thread guide 66 and each thread guide 17a is much steeper than illustrated. Post 21 is hollow and mechanical force transmitting linkages and electric cables are guided through the interior of post 21 into housing 62.

The construction of housing 62 is best seen in FIG. 2. An inner housing 68 is mounted on top of post 21 and includes an annular wall 68a, a bottom wall secured to post 21, a filter plate 72, and a transverse wall 68a' dividing the inner chamber 68b into a lower chamber portion and an upper chamber portion. The rotor 69c of a tangential blower is located in the upper chamber portion, and the motor 69a is connected to rotor 69c by a shaft located in a bearing passing through a central opening in the intermediate wall 68a'. A flange outwardly projecting from the bearing is secured by screws to the intermediate wall 68a' so that the blower and its motor are supported within the inner housing 68. The flange construction seals the lower chamber portion from the upper chamber portion. The blower has no outer housing so that the rotor 69 draws air in axial direction through the filter 72 and blows the air outwardly in tangential direction along the entire outer periphery thereof. The annular inner wall 68a, has a plurality of circumferentially spaced openings or slots 70 communicating with the inner chamber portion surrounding rotor 69c. An outer annular wall 68c surrounds the inner annular wall 68a and is spaced from the same. A plurality of circumferentially spaced thread guides, forming part of thread breakage indicating devices, are mounted at the lower annular free edge of wall 68c, outwardly projecting from the same in radial directions. An annular gap is formed between the inner annular wall 68a and the lower annular edge of the outer annular wall 68c. A top wall 68d extends between the upper annular edges of wall 68a and 68c and forms an annular chamber 74 with walls 68a and 68c. The upper annular portion 68c' of wall 68c is outwardly curved and has a plurality of circumferentially spaced openings 71 which are downward and outward directed as indicated by the two lower arrows in FIG. 2. Openings 71 are preferably slots longer in circumferential direction, as best seen in FIG. 1. The electric cables guided through the interior of post 21 includes conductors for supplying a voltage to motor 69a, and also to thread breakage indicators, not shown, controlled by thread guides 66, which are pivotally mounted on wall 68a, and respond with a pivotal movement when no thread passes through a thread guide due to breakage of the thread or exhaustion of a package 61. This construction is known and not an object of the present invention.

A lower housing portion 73 has a bottom wall with a central opening supported on a flange 21a of post 21. The upper edge of the lower housing portion 73 extends to the lower surface of the annular wall 68c so that the chamber 74 and the chamber 73a within the lower housing 73 form a larger closed chamber. The outer wall of the lower housing portion 73 has openings through which thread guides 66 pass.

When motor 69a operates, rotor 69c draws air in axial direction through filter 72 and blows the air outwardly along the entire periphery thereof so that the air passes through the circumferentially spaced slots or openings 70 into chamber 74 and from there through slots or openings 71 in the direction indicated by the arrows. Due to the downward slant of opening 74, and to the guiding of the air stream by the curved guide portion 68c', the air streams along the entire circumference of the outer annular wall 68c are downwardly and outwardly directed to blow any dust developed by abrasion of the threads 67 passing through the thread guides 66 at an acute angle, beyond

the thread guides and in outward directions away from the machine so that the dust cannot settle on the machine. Part of the air stream in chamber 74 passes below the lower edge of wall 68c and past thread guide 66 through the corresponding openings 73b in the lower housing portion 73. Only a smaller part of the air streams produced by rotor 69c goes this way, but this is sufficient to remove any dust which may settle on thread guides 66 so that the removed dust is further carried away by the strong air streams passing through openings 71 in outward radial directions.

It will be understood that each of the elements described above, or two or more together, may also find a useful application in other types of knitting machines, differing from the types described above.

While the invention has been illustrated and described as embodied in an apparatus for removing dust produced by thread guides on top of a circular knitting machine so that settling of the dust on the machine is prevented, it is not intended to be limited to the details shown, since various modifications and structural changes may be made without departing in any way from the spirit of the present invention.

Without further analysis, the foregoing will so fully reveal the gist of the present invention that others can, by applying current knowledge readily adapt it for various applications without omitting features that, from the standpoint of prior art, fairly constitute essential characteristics of the generic and specific aspects of this invention and, therefore such adaptations should and are intended to be comprehended within the meaning and range of equivalence of the following claims.

What is claimed as new and desired to be secured by Letters Patent is:

1. In a circular knitting machine including a support upwardly projecting at the top of the machine, in combination, housing means mounted on the top of said support and including an inner annular wall forming an inner chamber open on top and having circumferentially spaced first openings and an outer annular wall forming an annular chamber surrounding said inner chamber and having circumferentially spaced second openings; a plurality of circumferentially spaced thread guides mounted on said outer annular wall outwardly projecting from the same; and blower means located within said inner chamber and adapted to suck air from the openings on top of said inner chamber and to discharge the air along the entire circumference thereof through said first openings into said annular chamber and through said second openings at said outwardly projecting thread guides and beyond the same so that dust produced by threads passing through said thread guides is blown away from the machine in outward directions.

2. An apparatus as set forth in claim 1, and including a filter for closing said open top of said inner chamber so that the air drawn by said blower is filtered.

3. In a circular knitting machine including a support upwardly projecting at the top of the machine, in combination, housing means mounted on the top of said support and including an inner annular wall, a bottom wall, and an intermediate wall parallel to said bottom wall, said bottom and intermediate walls forming within said inner annular wall two inner chamber portions, the upper chamber portion being open on top, said inner annular wall having circumferentially spaced first openings communicating with said upper open inner chamber portion, a filter wall closing said open top of said upper inner chamber portion, said housing means including an outer annular wall forming an annular chamber surrounding said inner wall and having circumferentially spaced second openings; and a plurality of circumferentially spaced thread guides mounted on said outer wall outwardly projecting from the same; and blower means including a motor located within said closed inner chamber portion and a rotor located within said open upper inner chamber

portion for sucking air in axial direction through said filter wall and for blowing air outwardly around the entire periphery thereof through said first openings into said annular chamber and through said second openings toward the outwardly projecting portions of said thread guides and beyond the same so that dust produced by threads passing through said thread guides is blown away from the machine in outward directions.

4. In a circular knitting machine including a support upwardly projecting at the top of the machine, in combination, housing means mounted on the top of said support and including an inner annular wall forming an inner chamber and having circumferentially spaced first openings and an outer annular wall forming an annular chamber surrounding said inner chamber and having circumferentially spaced second openings, said outer annular wall having a free lower annular edge forming an annular gap with said inner annular wall, and a top wall extending between the top edges of said annular inner and outer walls, and closing said annular chamber on top; a plurality of circumferentially spaced thread guides mounted on said lower annular edge of said outer annular wall below the same outwardly projecting from the same; and blower means located within said inner chamber for blowing air outwardly through said first openings into said annular chamber and past said lower annular edge at said thread guides, and also through said second openings toward the outwardly projecting portions of said thread guides and beyond the same so that dust produced by threads passing through said thread guides is blown away from the machine in outward directions.

5. In a circular knitting machine including a support upwardly projecting at the top of the machine, in combination, housing means mounted on the top of said support and including an inner annular wall forming an inner chamber and having circumferentially spaced first openings and an outer annular wall forming an annular chamber surrounding said inner chamber and having circumferentially spaced second openings, said outer annular wall having a free lower annular edge forming an annular gap with said inner annular wall, and a top wall extending between the top edges of said annular inner and outer walls, and closing said annular chamber on top; a plurality of circumferentially spaced thread guides mounted on said lower annular edge of said outer annular wall below the same outwardly projecting from the same; a lower housing portion supported on said support and having an open upper end bounded by an upper annular edge located adjacent said lower annular edge of said housing means for closing said outer annular chamber, said lower housing portion having a plurality of circumferentially spaced openings through which the outer portions of said thread guides project; and blower means located within said inner chamber for blowing air outwardly through said first openings into said annular chamber and past said lower annular edge and through said openings in said lower housing portion along said thread guides, and also through said second openings toward the outwardly projecting portions of said thread guides and beyond the same so that dust produced by threads passing through said thread guides is blown away from the machine in outward directions.

6. In a circular knitting machine including a support upwardly projecting at the top of the machine, in combination, housing means mounted on the top of said support and including an inner annular wall forming an inner chamber and having circumferentially spaced first openings and an outer annular wall forming an annular chamber surrounding said inner chamber and having circumferentially spaced second openings, said outer annular wall having a free lower annular edge forming an annular gap with said inner annular wall, and a top wall extending be-

tween the top edges of said annular inner and outer walls, and closing said annular chamber on top; a plurality of circumferentially spaced thread guides mounted on said lower annular edge of said outer annular wall below the same outwardly projecting from the same; a lower housing portion supported on said support and having an open upper end bounded by an upper annular edge located adjacent said lower annular edge of said housing means for closing said outer annular chamber, said lower housing portion having a plurality of circumferentially spaced openings through which the outer portions of said thread guides project, said housing means including a top wall extending between the upper annular edges of said inner and outer annular walls and closing said annular chamber on top, said top wall having an annular portion outwardly projecting from said outer annular wall and having a curved downwardly and outwardly directed lower surface; and blower means located within said inner chamber for blowing air outwardly through said first openings into said annular chamber and past said lower annular edge and through said openings in said lower housing portion along said thread guides, and also through said second openings toward the outwardly projecting portions of said thread guides and beyond the same, said outwardly projecting annular portion of said top wall guiding the air streams passing through said second openings in downward and outward directions so that dust produced by threads passing through said thread guides is blown away from the machine in outward and downward directions.

30 7. A circular knitting machine as set forth in claim 6 wherein said housing means include a bottom wall closing one end of said inner chamber and secured to said support, an intermediate wall parallel to said bottom wall within said inner chamber connected to said annular inner wall, and a filter closing the ends of said inner chamber remote from said bottom wall; and wherein said blower means include a motor mounted on said intermediate wall and located between the same and said bottom wall, and a rotor located between said intermediate wall and said filter, said first openings being located in a portion of said inner annular wall in the region of said rotor.

8. A machine as set forth in claim 6 wherein said support is a hollow post located in the main axis of the circular knitting machine, said post being hollow and adapted to enclose electric cables connected to said motor.

9. A circular knitting machine as set forth in claim 6 wherein said support is a post located in the main axis of said circular knitting machine and having an upper end supporting said housing means, and a lower flange spaced from said upper end and supporting said lower housing portion, said lower housing portion having a bottom wall with a central opening through which said post passes, the portion of said bottom wall surrounding said central opening resting on said flange of said post.

55 10. A circular knitting machine as set forth in claim 6, wherein said first and second openings are circumferentially elongated slots.
